UNITED STATES PATENT OFFICE.

ERNEST A. HOUCHEIN, OF NEW YORK, N. Y.

CANDLE-FORMING MACHINE.

Application filed September 27, 1920. Serial No. 413,125.

To all whom it may concern:

Be it known that I, ERNEST A. HOUCHEIN, a citizen of the United States of America, residing at New York, N. Y., have invented

5 a new and useful Candle-Forming Machine, of which the following is a specification.

My invention relates particularly to a machine for molding candles from wax or other ordinary candle compositions.

10 The main object is to provide a machine for molding tapered candles and particularly those having a projecting tip portion. I have particularly sought to construct a machine in which the candles may be formed

15 rapidly and accurately and at a minimum cost.

In the form shown herein, the candle is molded upside down or inverted, the base being smaller in diameter than the rim of

20 the candle. A plurality of tapered molds are mounted in a hollow frame into which the melted wax is poured. The bottom of each mold which is shaped to form the desired design of tip of the candle is formed

25 by a spring pressed plunger which also carries a wire or rod for forming the wick passage. The molds and plungers are adapted to be separated from each other so that the candles may be ejected downwardly.

30 Fig. 1 is a plan view of a machine embodying the improvements of my invention parts being broken away so as to show some of the plungers and part of the channels for circulating the heating or cooling medium.

35 Fig. 2 is a side view of the same, part being broken away and showing two of the molds in side elevation and one in section.

Fig. 3 is a vertical cross sectional view of the molding frame with one mold in place.

40 Fig. 4 is a vertical projection of the right hand end of the machine showing part of the mechanism for lifting and lowering the mold frame, part of the casing being broken away to show the gears inside.

45 Fig. 5 is a vertical projection of the opposite end of the machine with part of the end of the machine broken away to show the parts inside.

Fig. 6 is a vertical sectional view showing

50 a part of the mold frame and one of the mold units.

Fig. 7 is an elevation of part of the mechanism for lifting and lowering the mold frame.

Fig. 8 is a perspective view of one of the 55 candles formed in this machine.

As shown in Fig. 8, the candle 10 formed on this machine is smaller in diameter at the bottom than it is at the rim and the upper end may be formed with grooves or tapered, 60 as desired. It should be understood that the wick is inserted after the candle is formed.

Each candle is formed in a tapered mold 11 which is smaller at the top than at the 65 bottom and screwed into the upper and lower walls of the hollow mold frame 12. The bottom of each mold is formed by a plunger 13 which carries the wick forming core 14.

70 Each plunger is mounted on the upper end of a rod 15. The upper end of the rod extends into a socket 16 in the bottom of the plunger and the two parts are secured together by a pin 17. Each rod is guided in 75 plates 18 and 19. A spring 20 surrounding rod 15 presses against a plate 18 and the lower end of the socket 16 on the plunger so as to push the rod and plunger upward. The upward movement of the rod 15 is 80 limited by a cotter pin 21 when the mold frame is disengaged from the plungers. Each mold 11 is provided with a shoulder 22 adapted to seat on the upper edge of its plunger 13. As a result of this construction, 85

it will be seen that when the mold frame and plungers are engaged with each other, each plunger enters the tapered lower end of the corresponding mold and thus each plunger is guided accurately to its seat in 90 its mold tube even though the molds or the plungers are not accurately located with respect to each other. It is possible therefore with such a construction to get accurate results without the very accurate location of 95 the relative parts which would be very expensive. This construction also insures accurate results even though the individual parts may become somewhat relatively displaced with respect to each other.

100 Cooling water or a heating medium may be introduced to the mold frame through an

opening 23 and flow out through an outlet 24. To distribute the cooling or heating medium a trough 25 may be provided with a number of small outlets such as 26 so that as the medium is introduced in the opening 23 into the trough 25 it will be distributed into the spaces between the molds throughout the length of the trough 25. It will then circulate between the molds and return and pass through the outlet 25.

The mold frame and the plungers with co-operating parts are movable relatively to each other. The mold frame 12 is provided with side flanges 27 and end flanges such as 28. In the illustrative form shown, the frame is vertically movable and guided in the corner pieces 29. Depending from each end of the mold frame are racks 30 and 31 which mesh respectively with the gears 32 and 33. On the right hand end of the machine as viewed in Figs. 1 and 2 is mounted a handle 33' to which is secured a gear 34 which meshes with the gear 35. The latter is secured to a gear 36 which meshes with one of the gears 32 so that when the handle 33' is rotated it rotates gears 32—32. The gears 35 and 36 are mounted on a shaft 37 which extends from the right hand end of the machine to the left hand end where it has a gear 38 meshing with one of the gears 33 so that the gears 32 and 33 rotate together to raise and lower the opposite ends of the mold frame simultaneously. It should be understood that the machine would function in the same manner if the plungers 13 and plates 18—19 constituted the movable member instead of the mold frame as shown.

A suitable brake as shown for example in Figure 7 may be employed to prevent the movable member, in this case the mold frame, from falling too rapidly when it is being lowered. On one of the shafts, for example, the shaft carrying the handle, is mounted a brake drum 40, and a brake band 41 encircles the latter. The ends of the band are secured to a lever 41'' pivoted at 42 to a stationary part of the frame. The lever 41'' has an extension arm 43 movable therewith. Pivoted to the arm 43 as at 44 is a link 45 having a tail or extension 46. The shaft 47 is mounted in the frame and carries thereon a bell crank lever having arms 48—49. The link 45 is pivoted as at 50 to one arm of the bell crank lever. A rod 51 having a spring 52 for urging it in one direction is secured to a part, for example, the pivot 44. On the shaft 37 is mounted a ratchet 53, and a co-operating pawl 54 is pivoted to the frame as at 55. The pawl 54 and lever 45 are so positioned that the tail 46 when in one position engages the pawl and disengages the latter from the ratchet. With the parts shown in Fig. 7 in the full line positions, the brake band is disengaged from the drum and the

pawl is engaged with the ratchet. In this position the handle may be turned and the racks elevated. Due to the relative positioning of the pivots 42, 44, 47 and 50, the spring will be kept in its compressed condition and the brake band disengaged from the drum.

When it is desired to lower the racks, the arm 49 of the bell crank lever is moved toward the left as viewed in Fig. 7 to the dotted line position. The tail 46 will then contact with the pawl and disengage the latter from the ratchet. A spring 52 will expand and draw the arm 43 downwardly to cause the brake band to grip the drum and prevent the movable member, in the example shown, the mold frame, from falling too rapidly. The tension of the spring 52, and consequently, the tension of the brake band, may be varied by means of the wing nut on the lower end of the rod 51.

The candles are molded when the parts are in the position shown in Figs. 5 and 6 by simply pouring the melted wax or other composition into the top of the mold frame, the wax running into the tubes 11 about the cores 14 and solidifying. This solidification may be hastened by introducing cooling water into the mold frame as above mentioned. When the wax has hardened the mold frame is raised by rotating the handle 33 so as to strip the mold frame and the candles carried thereby from the plungers and the wick cores into the position shown in Figs. 2 and 4. A platen 40' is then inserted beneath the candles and supported on flanges such as 41'. This platen may be provided with a suitable yielding upper face so as to prevent marring the tips of the candles when they are ejected from the molds. This platen may also be divided into sections or provided with pockets or recesses by intersecting partitions or wires, if desired. After the platen has been inserted the part 42' of the wax to which the candle portions 10 are secured may be cut off or stripped by means of suitable knives operated along the upper surface of the mold frame 12. When this part 42' has been removed the candles if they do not fall out automatically may be ejected downwardly from the molds 11 by simply pressing on the bases of the candles which are uppermost.

I claim:

1. A candle molding machine comprising, a plurality of plungers each designed to mold the tip of a candle, a vertically movable frame, downwardly diverging molds carried thereby above said plungers and a platen adapted to be inserted between the plungers and the molds to receive the molded candles from said downwardly diverging molds.

2. A candle molding machine comprising, a plurality of plungers each designed to

5 mold the tip of a candle, wick cores carried by said plungers, a frame, downwardly diverging molds carried thereby above said plungers, means for separating said molds and plungers and a platen adapted to be inserted between the plungers and the molds.

10 3. A candle molding machine comprising, a plurality of plungers each designed to mold the tip of a candle, a frame, downwardly diverging molds carried thereby above said plungers, a toothed rack carried by one of said members, a gear meshing with said rack and means for rotating said gear to move the frame and plungers relatively 15 to each other to either separate or cause said members to engage each other.

15 4. A candle molding machine comprising, a plurality of resiliently mounted plungers each designed to mold the tip of a candle, a vertically movable frame, tapered molds carried thereby above said plungers and means for raising said molds above said plungers.

20 5. In a candle molding machine, a mold frame, tapered downwardly diverging molds carried by said frame, a plunger designed to mold one end of a candle cooperating with each of said downwardly diverging tapered molds, and means for moving said tapered molds and cooperating plungers relatively 25 to each other to cause the plungers to be disengaged from and separated from the molds.

30 6. In a candle molding machine, a plurality of plungers, a hollow mold frame, tapered molds screwed into the bottom and top of said frame and means for lifting said mold frame and molds clear of said plungers.

35 7. In a candle molding machine, a plurality of plungers with cores carried by said plungers, a hollow mold frame, tapered molds screwed into the bottom and top of said frame and means for lifting said mold frame and molds clear of said plungers.

40 8. In a candle molding machine, a plurality of resiliently supported plungers, a mold frame, tapered molds carried thereby above said plungers, and means for moving said molds and plungers into and out of contact with each other, said molds being free of 45 obstructions when the molds and plungers are moved out of contact.

45 9. In a candle molding machine, a vertically movable frame, plungers below said frame, resilient means for moving said plungers into engagement with said frame, racks depending from said frame, gears meshing with said racks, a handle and gearing between said handle and gears for raising and lowering said frame.

50 10. In a candle forming machine, a tapered mold member having an interior shoulder, a spring pressed plunger member mounted below said mold member and means for raising and lowering one member relative 55 to the other whereby the plunger member

may be separated from the mold member and the latter left free of obstruction.

11. In a candle forming machine, a tapered mold member having an interior shoulder, a plunger member mounted below said mold for co-operation therewith, a spring for moving said mold and plunger members into engagement with each other, a wick core carried by said plunger and means for moving one of said members relatively to the other. 70 75

12. In a candle forming machine, a tapered mold having an interior shoulder, a spring pressed plunger mounted below said mold and adapted to be moved into contact with said shoulder and means for supporting a platen between the mold and the plunger when the latter are separated. 80

13. In a candle forming machine, a mold, a plunger below said mold having a depending socket, a rod connected in said socket, a spring surrounding said rod and a stationary abutment for said spring. 85

14. In a candle forming machine, a tapered mold, a plunger below said mold, means including a spring for moving one of said members relatively to the other to permit them to be engaged with each other and to center the plunger and resiliently hold said mold and plunger in engagement. 90 95

15. In a candle forming machine, a tapered mold, a plunger below said mold, a wick core carried by one of said members, means for moving said mold and said plunger into engagement with each other and resiliently holding them in engagement and centering the plunger. 100

16. In a candle forming machine, a tapered mold, a spring pressed plunger below said mold, means for moving said mold and plunger into contact with each other, and centering the plunger and a support for a platen between the mold and the plunger. 105

17. In a candle forming machine, a tapered mold, a spring pressed plunger below said mold, a wick core carried by said plunger, means for moving said mold and plunger relatively to each other and centering the plunger, and a support for a platen between the mold and the plunger. 110 115

18. In a candle forming machine, a mold member, a plunger member mounted for co-operation with said mold, one of said members being movable relatively to the other, resilient means for holding said mold and plunger members in contact with each other, a wick core carried by said plunger and means for holding said movable member in one position. 120

19. In a candle forming machine, a mold member, a plunger member mounted for co-operation with said mold, resilient means for holding said mold and plunger members in contact with each other, means for moving one of said members relatively to the other 130

and a brake for retarding the movement of said movable member.

20. In a candle forming machine, a mold member, a plunger member mounted for co-operation with said mold, means for moving one of said members relatively to the other, a pawl and ratchet for holding said movable

member in one position, a brake for retarding the movement of said movable member and means operable upon the application of said brake for releasing said pawl and ratchet. 10

ERNEST A. HOUCHIN.
